UNITED STATES PATENT OFFICE.

HIRSH W. YANKELEWITZ, OF NEWARK, NEW JERSEY.

ADVERTISING AND AMUSEMENT APPARATUS.

Application filed June 26, 1926. Serial No. 118,664.

This invention relates particularly to apparatus for attracting the attention of the public and displaying advertisements but is susceptible of use for amusement purposes.

One object of the invention is to provide novel and improved apparatus of this character comprising an automaton or movable dummy figure which is automatically actuated to assume different postures, for example an acrobatic clown figure which is moved in simulation of acrobatic feats, and whereby a sign or other desirable inscription or device, etc., is automatically displayed or exhibited at some point in the cycle of operation of the figure so that the movements of the figure attract the attention of observers to it and thereby to the sign or other exhibit which is associated therewith.

Another object is to provide such apparatus embodying novel and improved features of construction wherein a plurality of signs or inscriptions, devices, etc., are successively displayed during successive cycles of operation of the apparatus whereby attention of the observer is concentrated upon each sign or inscription and indefinitely held to the apparatus in anticipation of the succeeding exhibits.

A further object is to provide apparatus of the general character described comprising a main frame and an auxiliary frame mounted on said main frame and comprising two pivotally connected sections normally disposed in substantially side-by-side relations, one of said sections having a plurality of signs or inscriptions or devices upon one side thereof movable relatively to a display position, so that when said section is pivotally moved relatively to the other section into end-wise relation, the sides thereof are reversed and one of said signs or inscriptions or devices is displayed on the other side of said main frame, said signs or devices being automatically moved step-by-step to and from said display position simultaneously with movement of said auxiliary frame.

Other objects are to provide such apparatus wherein said auxiliary frame is also movable about another axis at an angle to the first-mentioned axis in successive relation to the movement thereof about said first-mentioned axis, to concentrate and hold attention to the apparatus; to provide in apparatus of this character an endless belt having a plurality of signs or inscriptions, etc. there-

on, and novel and improved means for automatically moving said belt step-by-step in timed relation to the movement of said auxiliary frame; to provide a plurality of series of inscriptions or signs, etc., and novel and improved means for permitting selective display of any of said series; to provide such apparatus which is simple and inexpensive in construction and reliable in operation, and to obtain other results and advantages as are brought out by the following description.

Referring to the accompanying drawings, in which corresponding and like parts are designated throughout the several views by the same reference characters,

Figure 1 is a front elevation of an advertising or amusement apparatus embodying the invention, showing the same in normal position;

Figure 2 is a side elevation;

Figure 3 is a front elevation of the apparatus, showing the dummy figure in operation to display a sign or inscription;

Figure 4 is an enlarged elevation showing the apparatus in the position illustrated in Figure 1, with the covering of the figure and the walls of the base portion removed for clearness in illustration;

Figure 5 is a side elevation of the upper part of the apparatus illustrated in Figure 4;

Figure 6 is a rear elevation of the apparatus;

Figure 7 is an enlarged vertical longitudinal sectional view through the connection between the frame sections of the auxiliary frame, and the belt roller;

Figure 8 is an enlarged horizontal sectional view, taken on the line 8—8 of Figure 5;

Figure 9 is a transverse sectional view, taken on the line 9—9 of Figure 7;

Figure 10 is a bottom plan view of the apparatus illustrated in Figure 4;

Figure 11 is a fragmentary end elevation of the cam levers illustrated in Figure 10;

Figure 12 is an enlarged fragmentary plan view of a portion of the belt carrying the inscriptions to be displayed, showing the inscriptions arranged according to the invention;

Figure 13 is a similar view showing another arrangement of the inscriptions;

Figure 14 is a fragmentary perspective view of the belt;

Figure 15 is a detached perspective view of the cover or casing for the belt;

Figure 16 is a view similar to Figure 9 showing a modification of the pawl and ratchet mechanism for use with a belt as illustrated in Figure 13, and

5 Figure 17 is a side elevation of a modified cam for use with the pawl and ratchet mechanism shown in Figure 16.

For the purpose of illustrating the principles of the invention, I have shown it embodied in advertising apparatus which includes the dummy figure A of an acrobatic clown mounted upon a main frame comprising a hollow base B and the representation C of a ladder. The figure A is mounted 15 upon the ladder so as to assume the normal position shown in Figure 1 of the drawings and successively the positions shown by dotted lines in Figure 2 and by solid and dotted lines in Figure 3, whereby the figure is caused to simulate the position of standing on its hands upon the top of the ladder and oscillating upon one hand. The back of the figure carries a casing D representing a knapsack or pack within which is arranged 25 devices to be displayed, in the present instance a plurality of inscriptions each comprising one part of an advertising sentence. The inscriptions are displayed through a display opening in the casing D simultaneously with the movement of the figure into the position shown in Figure 3 of the drawings. The figure is caused to repeat the motions above described in successive cycles, and a different inscription is displayed during each cycle of operation.

Specifically describing the details of the apparatus, one of the stiles 1 of the ladder may be made solid while the other stile 2 is preferably in the form of a tube. An auxiliary frame is mounted upon the upper ends of the stiles 1 and 2 of the ladder and comprises sections E and F, the first of which includes a vertical side piece 3 having one end in the form of a simulation of a human hand, as indicated at 4, adapted to separably rest upon the top of the stile 1 of the ladder. The other side piece of said frame section E comprises a part 5 having one end thereof in simulation of a human hand, as at 6, and secured fast to the top of the tubular stile 2. The part 5 has pivotally connected thereto as at 7 another part 8 which is normally disposed substantially parallel to the side piece 3. The upper ends of the side pieces of the frame section E are fast connected together by a rod 9 one end of which may be riveted to one of the side pieces as at 10, while the other side piece may be threaded upon the other end of the rod as at 11. With this construction, it will be obvious that the frame section E may swing about the pivot 7 in a vertical plane laterally of the ladder portion C of the main frame.

The frame section F comprises two side 65 pieces 12 and 13 each of which is fast se-

cured to a tubular shaft 14 revolvably mounted on the rod 9, and accordingly the frame section F has a pivotal relation to the frame section E and may normally assume a substantially side-by-side relation to the frame 70 section E, as shown in Figures 4, 5 and 6. The two frame sections are encased by a suitable fabric cover in simulation of clothing of the dummy figure A, the side pieces of the frame section E forming the arms of the figure while the frame section F forms the trunk and legs of the figure. The rod 9 corresponds to the shoulders of the figure. It will thus be seen that by moving the frame section F upwardly about the rod 9 as a pivot, the figure may assume the position shown by dotted lines in Figure 2 of the drawings.

For so swinging the frame section F relatively to the frame section E, I mount a pinion 15 on the tubular shaft 14 which meshes with a rack bar 16 slidably mounted upon the frame section E. One end of the rack bar is pivotally connected to a link 17 which passes downwardly through the base 69 of the part 5 of the frame section and through the tubular stile 2 of the ladder into the base portion of the apparatus, where the link is pivotally connected at 19 to one end of a lever 20 the other end of which is pivotally connected at 21 to the base frame 22. The lever 20 has a roller 23 which engages a cam 24 fast on a horizontal shaft 25 revolvably mounted in the base frame 22. A spring 26 maintains the roller 23 in engagement with the cam, and the cam is so shaped (see Figure 4 of the drawings) that upon rotation thereof the lever 20 is first pushed downwardly so as to actuate the rack bar 16 and rotate the tubular shaft 14 to swing the frame section F upwardly, as shown in dotted lines in Figure 2 of the drawings, after which the cam relieves the roller and the weight of the frame section cooperating with the spring 26 causes the frame section to return to its normal position, as shown in Figures 1 and 5.

Any suitable means may be utilized for rotating the shaft 25, but in the present instance I have shown a large gear 27 fast upon the shaft and driven through a train of gears 28 from an electric motor 29 secured to the base frame 22.

The cam 24 has such contour as to retain the frame section F in its upper position for a certain period of time, and during this period the frame section E is oscillated about the pivot 7. To cause such oscillation, I may pivotally connect one end of a link 30 to the part 8 of the side piece of the frame section E in eccentric relation to the pivot 7, as at 31. The link 30 extends downwardly through the tubular stile 2 of the ladder and is connected at its other end as at 32 to one end of a lever 33 pivotally connected at its

opposite end co-axially with the lever 20. The lever 33 has a roller 34 which engages the periphery of a cam 35 mounted on the shaft 25, the roller being held in contact with the cam by a spring 36. The cam 35 is so shaped as to actuate the lever 33 so as to successively pull upon and release the link 30 several times during one rotation of the cam, and also to hold the auxiliary frame in tilted position, as shown by solid lines in Figure 3, for a short period of time. Of course, the cam 35 is timed with the cam 24 so that the auxiliary frame is not tilted until the frame section F has been raised to its uppermost position.

A roller 37 is mounted to rotate upon the tubular shaft 14 but is normally frictionally induced to rotate with said shaft by a spring washer 38. An endless belt 39 passes over said roller 37 and another roller 40 journaled on the frame section F, said belt also passing over a pair of idler rollers 41 intermediate the rollers 37 and 40. The belt is maintained under tension by mounting the roller 40 in slots 42 in the frame section F and utilizing tension springs 43 for normally drawing the roller 40 away from the roller 37. The roller 37 is formed with a plurality of teeth or projections 44 and the belt 39 is formed with corresponding openings 45 which receive the projections 44. The devices to be displayed, in the present instance a plurality of series of lines 46 constituting parts of advertising sentences, are arranged in spaced relation upon the outer surface of the belt 39. The casing D is removably fitted upon the frame section F so as in combination with the covering for the figure A to enclose the belt 39, but said casing is provided with a plurality of display openings or slots 47 through any of which one line 46 may be displayed at a time. The display openings 47 are provided with removable closure slides 48 whereby any one of the openings may be selectively used for display of the lines 46.

In accordance with the invention the belt 39 is longitudinally moved over the rollers 37 and 40 by and simultaneously with movement of the frame section F relatively to the section E, and this is accomplished by temporarily holding the roller 37 against movement with the tubular shaft 14, it being obvious that with the roller so held as the frame section F is moved, the belt 39 will move relatively to the display openings 47. For so holding the roller, I may provide a ratchet 50 fast to the roller with which cooperates a pawl 51 which is periodically moved into and out of engagement with the ratchet by means of a link 52 which may be in the form of piano wire, and extends downwardly through the tubular stile 2 of the ladder and is connected to a lever 53 similar to the lever 20. The lever 53 has

a roller 54 engaging a cam 55 and the roller is held in engagement with the cam by a spring 56. The cam is so shaped and timed with the cam 24 that when the frame section F starts its movement toward its upper position, the pawl 51 is forced into engagement with the ratchet 50 and is so held in engagement for a period of time sufficient to produce the desired movement of the belt 39, after which the pawl is released from the ratchet by action of the cam 55 and spring 56. Upon return of the frame section F to its normal position the roller 37 moves with the shaft 14 so that the belt remains stationary.

The lines 46 or other inscriptions, etc., may be arranged on the belt in any suitable manner, but I have shown in Figure 12 three series of lines 46 each of which constitutes one part of an advertising sentence, and the lines of the series are spaced in alternate relation according to the spacing of the display openings 47 in the casing D, so that according to the display opening 47 which is being used one line of the same sentence will be displayed upon each movement of the frame section F. As shown, one sentence comprises the lines a, b, c and d, while another sentence comprises the lines e, f, g and h, and another sentence includes the lines i, j, k and l, three sentences being illustrated. In operation of the display apparatus, only one of the openings 47 is used at a time, and when it is desired to cease display of the particular sentence corresponding to said opening, the closure 48 is applied and the closure 48 of another opening 47 corresponding to the sentence desired to be displayed, is removed. Of course, the size of the roller 37 and the period during which it is held against movement, will be so related to the spacing of the display openings 47 and the movement of the frame section F as to properly locate the lines 46 at the respective display openings 47.

The arrangement of the inscriptions or lines shown in Figure 12 is particularly adaptable for use where there will be an attendant to the apparatus for changing the closures 48 of the casing D to successively display the different sentences, and as will be seen from Figure 9 of the drawings, with this arrangement the ratchet 50 has two diametrically opposite recesses 57 to cooperate with the tooth 58 of the pawl, one recess 57 being moved out of cooperative relation with the tooth 58 each time the frame section F returns to normal position and the other of said recesses 57 being simultaneously moved into cooperative relation with the tooth 58. Where it is desired to successively display the different sentences without an attendant, the lines of each sentence may be arranged in succession, as shown in Figure 13. There are six lines to each sen-

tence, and accordingly the ratchet to cooperate with such an arrangement would have six recesses 59, as shown in Figure 16 of the drawings, so that the roller 37 is held against movement with the shaft 14 during approximately one-sixth of a complete revolution of said shaft instead of a half revolution as in the construction shown in Figure 9. A modified form of cam is also necessary, as shown in Figure 17, for maintaining the tooth 58 of the pawl in engagement with the ratchet during one-sixth of a revolution of the shaft. With this form of the invention only one display opening 47 is used for all of the sentences, and the beginning of each separate sentence is automatically displayed immediately after the ending of the preceding sentence.

It is desirable to provide for a large variation of signs or other devices to be displayed, and accordingly the belt 39 is preferably so constructed as to be easily and quickly applied to and removed from the rollers 37 and 40. Thus the ends of the belt may be formed with cooperating loops and notches 60, 61, the loops being adapted to removably receive a locking pin 62 longitudinally movable through the loops, whereby the ends of the belt may be separably connected.

Obviously, the character of the device to be displayed may be as desired, that is either for advertising purposes or for amusement, and of course other means than the specific belt 39 may be utilized for moving the devices to be displayed into and out of display position. The devices might be the lines of fortune telling sentences and the apparatus might be combined with a coin-actuated apparatus, whereby the deposit of a coin is necessary before the operation of the figure and the display mechanism is possible. Also, the device to be displayed might be other than an inscription or a sentence, for example, the device might be a figure or an article. Accordingly, the term "device to be displayed" used in the claims is intended to cover any signs, inscriptions, articles, etc., which might be used with the apparatus.

While I have shown and described the invention as embodied in certain details of construction and for certain particular purposes, it will be understood that this is primarily for illustrating the principles of the invention and that many modifications and changes may be made in the details of construction and the device used for other purposes, without departing from the spirit or scope of the invention. Therefore, I do not desire to be understood as limiting myself except as required by the following claims when construed in the light of the prior art.

Having thus described the invention, what I claim is:

1. Apparatus of the character described,

comprising a support, a dummy figure mounted on said support and including two sections pivotally connected at one end and normally disposed in side-by-side relation, one of said sections having the end opposite said pivotal connection connected to said support and forming the arms and hands of said figure, the other section constituting the trunk or body and feet of the figure and said pivotal connection corresponding to the shoulders of the figure so that the figure normally appears to stand in upright position on its feet, whereby pivotal movement of the second-mentioned section into endwise relation to the first-mentioned section causes the figure to appear to stand on its hands upon said support, a device to be displayed mounted upon the second-mentioned section and movable into and out of display position on the side thereof corresponding to the back of the figure, and an operative connection between said device and the other of said sections whereby relative pivotal movement of said sections into endwise relation reverses the second-mentioned section and moves said device into display position so that said device is normally invisible from the front of said figure and is displayed when the figure moves into the position of standing upon its hands, and means for moving the second-mentioned section alternately from one of said positions to the other about said pivotal connection.

2. In apparatus of the character described, the combination of a frame comprising two sections, a shaft revolvably mounted on one of said sections, the other of said sections being fast upon said shaft whereby said sections are pivotally connected, a pinion fast on said shaft, a rack meshing with said pinion and reciprocably mounted on the first-mentioned section, means for reciprocating said rack to swing the second-mentioned section about said pivotal connection, a device to be displayed mounted on said second-mentioned section movable into and out of display position, and an operative connection between said device and the other section whereby movement of the second-mentioned section produces movement of said device.

3. In apparatus of the character described, the combination of a frame comprising two sections pivotally connected at one end and normally disposed in side-by-side relation, a device to be displayed mounted upon one of said sections and movable into and out of display position upon one side of said section, and an operative connection between said device and the other of said sections, whereby relative pivotal movement of said sections into endwise relation reverses the first-mentioned section and moves said device into display position.

4. In apparatus of the character de-

scribed, the combination of a frame comprising two relatively movable sections, an endless belt frictionally passing over a part of each of said sections and having a device to be displayed and movable by said belt into and out of display position, and means for holding said belt against and releasing it for longitudinal movement relatively to one of said parts upon relative movement of said sections, in opposite directions respectively, whereby said device is moved into display position upon relative movement of said sections in one direction.

5. In apparatus of the character described, the combination of a frame comprising two sections pivotally connected at one end and normally disposed in side-by-side relation, a roller journaled co-axially with said pivotal connection, an endless belt passing around and frictionally engaging said roller and a part of one of said sections and having a device to be displayed movable by said belt into and out of display position upon one side of said section, and means for holding said roller against and releasing it for rotation upon relative pivotal movement of said sections in opposite directions respectively, whereby said device is moved into display position upon relative movement of said sections in one direction.

6. In apparatus of the character described, the combination of a main frame, an auxiliary frame comprising two sections pivotally connected at one end and normally disposed in side-by-side relation, a device to be displayed mounted upon one of said sections and movable into and out of display position upon one side of said section, an operative connection between said device and the other of said sections, whereby relative pivotal movement of said sections into end-wise relation reverses the first-mentioned section and moves said device into display position, and means pivotally connecting the second-mentioned section of said auxiliary frame upon said main frame on an axis at an angle to the axis of said pivotal connection between said sections.

7. In apparatus of the character described, the combination of a main frame, an auxiliary frame comprising two sections pivotally connected at one end and normally disposed in side-by-side relation, a device to be displayed mounted upon one of said sections and movable into and out of display position upon one side of said section, an operative connection between said element and the other of said sections, whereby relative pivotal movement of said sections into end-wise relation reverses the first-mentioned section and moves said device into display position, means pivotally connecting the first-mentioned section of said auxiliary frame upon said main frame on an axis at an angle to the axis of said pivotal connection

between said sections, means for producing relative pivotal movement of said auxiliary frame sections, and means for moving said auxiliary frame about its pivotal connection to said main frame.

8. In apparatus of the character described, the combination of a main frame, an auxiliary frame comprising two sections pivotally connected at one end and normally disposed in side-by-side relation, a device to be displayed mounted upon one of said sections and movable into and out of display position upon one side of said section, an operative connection between said device and the other of said sections, whereby relative pivotal movement of said sections into end-wise relation reverses the first-mentioned section and moves said device into display position, means pivotally connecting the first-mentioned section of said auxiliary frame upon said main frame on an axis at an angle to the axis of said pivotal connection between said sections, means for producing relative pivotal movement of said auxiliary frame sections and for temporarily holding said sections in position to display said device, and means for moving said auxiliary frame about its pivotal connection to said main frame while said auxiliary frame sections are so held.

9. In apparatus of the character described, the combination of a main frame, an auxiliary frame comprising two sections pivotally connected at one end and normally disposed in side-by-side relation, a roller journaled co-axially with said pivotal connection, an endless belt passing around and frictionally engaging said roller and a part of one of said sections and having a device to be displayed movable by said belt into and out of display position upon one side of said section, means for holding said roller against and releasing it for rotation upon relative pivotal movement of said sections in opposite directions respectively, whereby said device is moved into display position upon relative movement of said sections in one direction, means for producing relative pivotal movement of said auxiliary frame sections and for temporarily holding said sections in position to display said device, and means for moving said auxiliary frame about its pivotal connection to said main frame while said auxiliary frame sections are so held.

10. In apparatus of the character described, the combination of a frame comprising two sections, a shaft revolvably mounted on one of said sections, the other of said sections being fast upon said shaft whereby said sections are pivotally connected, a roller frictionally mounted upon said shaft and capable of rotating relatively thereto, an endless belt passing around and frictionally engaging said roller and a part

of the second-mentioned section and having a device thereon to be displayed movable by said belt into and out of display position, means for rotating said shaft to produce pivotal movement of the second-mentioned section, and means for temporarily holding said roller against rotation with said shaft during said pivotal movement, whereby said device is moved into display position.

10 11. In apparatus of the character described, the combination of a frame comprising two sections, a shaft revolvably mounted on one of said sections, the other of said sections being fast upon said shaft whereby said sections are pivotally connected, a roller frictionally mounted upon said shaft and capable of rotating relatively thereto, an endless belt passing around and frictionally engaging said roller and a part 15 of the second-mentioned section and having a device thereon to be displayed movable by said belt into and out of display position, means for rotating said shaft to produce pivotal movement of the second-mentioned section, a ratchet fast connected to said roller, a pawl cooperating with said ratchet, and means for actuating said pawl into and temporarily holding it in engagement with said ratchet during said pivotal 20 movement of said frame sections whereby said device is moved into display position.

12. In apparatus of the character described, the combination of a frame comprising two sections, a shaft revolvably mounted 25 on one of said sections, the other of said sections being fast upon said shaft whereby said sections are pivotally connected, a roller frictionally mounted upon said shaft and capable of rotating relatively thereto, an 30 endless belt passing around and frictionally engaging said roller and a part of the second-mentioned section and having a device thereon to be displayed movable by said belt into and out of display position, means for 35 rotating said shaft to produce pivotal movement of the second-mentioned section, and means for periodically holding said roller against movement and periodically releasing it for movement during said pivotal movement of said frame sections, whereby said 40 device is successively moved into and out of display position.

13. The apparatus set forth in claim 10 with the addition of a main frame, means for pivotally connecting the first-mentioned frame section upon said main frame on an axis at an angle to the axis of the pivotal connection of said frame sections, and means for moving the first-mentioned frame about its pivotal connection to said main frame. 55 60

14. The apparatus set forth in claim 10 wherein the means for producing pivotal movement of said shaft also temporarily holds said frame sections in position to display said device, and with the addition of a main frame, means for pivotally connecting the first-mentioned frame section upon said main frame on an axis at an angle to the axis of the pivotal connection of said frame sections, and means for moving the first-mentioned frame about its pivotal connection to said main frame while said frame sections are held in said position to display 65 70 75 said device.

15. In apparatus of the character described, the combination of a casing having a plurality of spaced and parallel display openings, closures for said openings, a plurality of series of devices to be displayed, and means for moving said series of devices in spaced relation step-by-step so that the devices of each series are successively located at the same one of said display openings one upon each step of movement, whereby the plurality of series may be selectively and 80 85 90 separately displayed by removing the closure of the respective display opening. 95

16. In apparatus of the character described, a plurality of series of devices to be displayed, the devices of each series being spaced equidistantly in alternate relation to the devices of the other series, a casing enclosing said devices and having a plurality of display openings one for each of said series of devices, and means for moving said devices with a step-by-step motion in steps of distances equal to the spacing of the devices of each series, and separate closures for said openings whereby the plurality of series of devices may be selectively and separately displayed by removing the closure of the respective display opening. 100
